DESIGN FOR AN ASH TRAY

Boris Blecher, Philadelphia, Pa.

Application November 1, 1946, Serial No. 134,448

Term of patent 14 years

(Cl. D85—2)

To all whom it may concern:

Be it known that I, Boris Blecher, a citizen of the United States and a resident of Philadelphia, county of Philadelphia, State of Pennsylvania, have invented a new, original, and ornamental Design for an Ash Tray, of which the following is a specification, reference being had to the accompanying drawings, forming a part thereof, wherein:

Figure 1 is a perspective view of an ash tray showing my new design;

Figure 2 is an edge elevational view thereof; and

Figure 3 is a top plan view thereof.

I claim:

The ornamental design for an ash tray, as shown.

BORIS BLECHER.
